UNITED STATES PATENT OFFICE.

JAMES H. RAND, OF NEWTON, MASSACHUSETTS.

BUFFER FOR SWINGING INDICATOR-FRAMES.

1,077,555.

Specification of Letters Patent.

Patented Nov. 4, 1913.

Application filed April 5, 1912. Serial No. 888,710.

To all whom it may concern:

Be it known that I, JAMES H. RAND, a citizen of the United States, and resident of Newton, in the county of Middlesex and 6 State of Massachusetts, have invented new and useful Improvements in Buffers for Swinging Indicator-Frames, of which the following is a specification.

This invention relates to indicator devices 10 or index devices of the kind wherein a number of leaves or leaf frames are hinged in upright position upon suitable brackets or standards, each leaf frame having inwardly facing marginal channels, in which are held 15 the ends of removable and interchangeable indicator slips or cards, or transparent sheaths in which such slips or cards are incased. When these leaf frames are swung on their hinges, especially when two 20 or more of them are swung together with their opposed faces in engagement, and rubbing one against another, the inwardly bent flanges of the frames, forming the channels, tend to catch the edge of 25 the adjacent frame, thereby interfering with the free turning of the leaves, and tending to scratch and disfigure the device.

The principal object of my invention is 30 to overcome this objection. To this end I provide a buffer between the opposed faces 35 of the leaves adapted to prevent one leaf from engaging or scratching on the other when they are swung together. In its preferred form said buffer is of curved shape 40 to provide an easy riding surface for the frame engaged thereby, and is made in a strip of resilient sheet metal, similar in general contour to the indicator slips or cards, so as to be adjustable, removable and readily 45 interchangeable therewith in the frame. Such buffer may also carry as a part of itself an index tab projecting beyond the edge of the leaf frame.

Other features of the invention will hereinafter be described and particularly pointed out in the claims.

In the accompanying drawings which illustrate one embodiment of the invention,—Figure 1 is a perspective view, partly 50 broken away, of one of the hinged leaves of an indicator device, containing my invention; Fig. 2 is a cross sectional view, partly in plan, of two such leaf frames illustrating the operation of my invention; Fig. 3 is a 55 front elevation of my combined buffer and

tab device; and Fig. 4 is a section through the tab on line 4—4 of Fig. 2.

Referring to the drawings: *a*, *a* represent two leaf sections, secured together back to back in the usual manner, constituting the so hinged leaf or leaf frame. Several of such leaves or frames, in use, are mounted to swing on a bracket or standard (not shown), the relation of two of such frames when mounted on the bracket being disclosed in Fig. 2. Each leaf is provided in both sides with inwardly turned flanges *a'*, *a''*, forming inwardly facing marginal channels *a²*, *a³*, in which are held the ends of removable and interchangeable indicator strips *a⁴*.

When two or more leaves are swung together, the opposed faces of the leaves will rub together and the outer flange *a'* of one leaf will tend to catch on the outer edge of the adjacent leaf, unless provision is made to prevent it. For this purpose I attach to one or the other of the opposing faces of two adjacent leaves, or to both if desired, a buffer to prevent the leaves from engaging and rubbing one against the other when the leaves are turned together. As herein shown the buffer is formed from a strip *b* of resilient metal, which is preferably of the same breadth and length as the indicator strips *a⁴*. The ends of the strip *b* are held in the channels *a²* of the frame in the same manner as the strips *a⁴*, and the strip *b* may be removed from the frame by shortening or contracting it, by springing or bending said strip, to withdraw the ends from the channels. A part of the strip *b* near the outer margin of the leaf is bowed or curved outwardly as shown at *b'* to form a cap-like buffer projecting beyond the plane of the frame surface. This buffer is preferably made with a curved surface, as shown, to provide an easy bearing surface on which the adjacent frame will ride and slip, holding the opposed faces of the leaves out of engagement, the buffer bearing on the adjacent leaf frame as best shown in Fig. 2.

The metal strip *b* from which the buffer is formed may terminate at each end, if desired, in the frame channels. As herein shown, however, the buffer is combined with an indicator tab, projecting beyond the edge of the frame, carried by and preferably formed in an integral piece with the strip *b*. The strip *b* is bent or folded backward on itself to form a tongue *b²* to engage the

frame channel; thence it is bent outwardly again to extend across and beyond the flange a' ; and the projecting portion is folded back upon itself, forming a flat looped tab, the 5 free end of which b^5 is slipped and held between the two frame sections a, a . The projecting part of the strip forming the looped tab is made of relatively broad material, thus providing a tab b^4 of suitable breadth 10 and shape. A protective sheath b^6 of celluloid or other transparent material covers the tab b^4 and is held in place by tucking its ends between the two walls of the tab b^4 ; and an index sheet b^6 on which is inscribed 15 the desired character, is slipped between the metal tab b^4 and the transparent covering b^5 .

I claim:

1. In an indicator device, a hinged leaf frame provided with inwardly facing marginal channels, and a removable strip held at its ends by said channels and having a buffer projecting beyond the plane of the frame surface.

2. In an indicator device, a hinged leaf frame provided with inwardly facing marginal channels, and a removable strip held at its ends in said channels in a position transverse to the axis of the leaf, a portion of said strip being bowed outwardly to form 25 a buffer adapted to hold the faces of said leaf out of engagement with the next adjacent leaf.

3. In an indicator device, a hinged leaf frame provided with inwardly facing marginal channels, and a removable strip held at its ends by said channels in a position transverse to the axis of the leaf, a portion 35 of said strip closely adjacent to the outer margin of the leaf being bowed outwardly to form a buffer adapted to engage the marginal frame of the next adjacent leaf and hold the same out of engagement with the first named leaf.

4. In an indicator device, a hinged leaf frame provided with inwardly facing marginal channels, a removable strip held at its ends by said channels and having a buffer projecting beyond the plane of the frame surface adapted to hold the face of 45 said leaf out of engagement with the next adjacent leaf, and an indicator tab carried by said strip projecting beyond the edge of the frame.

5. In an indicator device, a hinged leaf frame provided with inwardly facing marginal channels, a removable strip held at 55

its ends by said channels and having a buffer projecting beyond the plane of the frame surface adapted to hold the face of said leaf out of engagement with the next adjacent leaf, and an indicator tab carried by and formed in an integral piece with said strip projecting beyond the edge of the frame.

6. In an indicator device, a hinged leaf frame provided with inwardly facing marginal channels, a removable strip held at its ends by said channels and having a buffer projecting beyond the plane of the frame surface adapted to hold the face of said leaf out of engagement with the next adjacent leaf, and an indicator tab carried by said strip projecting beyond the edge of the frame, the face of said projecting tab being broader than the face of said strip.

7. In an indicator device, a hinged leaf frame provided with inwardly facing marginal channels, a removable strip held at its ends by said channels and having a buffer projecting beyond the plane of the frame surface, and an indicator tab carried by said strip projecting beyond the edge of the frame, said tab being formed of sheet material broader than the strip and folded back upon itself.

8. In an indicator device, a hinged leaf frame comprising two sections secured back to back, provided with inwardly facing marginal channels, a removable strip held at its ends by said channels and having a buffer projecting beyond the plane of the frame surface, and an indicator tab carried by said strip projecting beyond the edge of the frame, said tab being formed of sheet material folded back upon itself to form a flat loop, the free end of said loop being held between said frame sections.

9. As a new article of manufacture, a combined buffer and tab for indicator frames, comprising a strip of metal having an outwardly curved portion forming a buffer, a relatively broad faced tab at one end, and a tongue between said tab and buffer adapted to engage said frame, all of said parts being formed of an integral strip of material.

Signed by me at Boston, Massachusetts, this 23rd day of March 1912.

JAMES H. RAND.
